UNITED STATES PATENT OFFICE.

WILLIAM RITSON WILSON, OF TORONTO, ONTARIO, CANADA.

RAILWAY-RAIL.

No. 903,937.

Specification of Letters Patent.

Patented Nov. 17, 1908.

Application filed February 17, 1908. Serial No. 416,327.

To all whom it may concern:

Be it known that I, WILLIAM RITSON WILSON, a citizen of the United States of America, resident of the city of Toronto, in the 5 county of York, Province of Ontario, in the Dominion of Canada, have invented certain new and useful Improvements in Railway-Rails, of which the following is a specification.

10 The invention relates to improvements in railway rails as described in the present specification and illustrated in the accompanying drawings that form part of the same.

15 The invention consists essentially in the novel construction and arrangement of parts whereby a separable head is held in place on the permanent head by a hooked flange on the 20 other and is rigidly secured by a plurality of bolts to said permanent head.

The objects of the invention are to reduce the cost of maintenance of ways and to devise a rail particularly adaptable for street 25 railway rails in which a worn head may be easily and quickly removed and replaced without disturbing the main portion of the rail and thus disrupting the roadbed and pavements.

30 In the drawings, Figure 1 is a sectional perspective view of a portion of a rail constructed in accordance with my invention. Fig. 2 is a longitudinal sectional view of a 35 portion of the rail through one of the bolt holes.

Like numerals of reference indicate corresponding parts in each figure.

Referring to the drawings, 1 is the permanent part of the rail having the base 2 and a web 3 and a permanent head 4, the 40 sides 5 and 6 of the said head 4 being unevenly distributed in relation to said web 3 to obtain a greater width on the side 5.

7 are slots arranged at intervals longitudinally in the side 5 of the head 4.

8 is the separable head of the rail having a longitudinal groove 9, in which the flange of the car wheel travels, and a downwardly extending inturned or hooked flange 10 at 50 one side thereof fitting snugly around and gripping the outer edge of the side 6 of the head 4, and a straight flange 11 from the other side abutting the outer edge of the side 5. The flanges 10 and 11 are formed 55 so that the distance between them is uniform from end to end of the rail and the distance

between them is such that when the inturned flange 10 is hooked over the edge of the head 4, the inner side of the flange 11 will bring the said flange 10 to grip the permanent 60 head on that side. The head of the rail is thus securely held from lateral displacement.

12 are bolt holes through the head 8 in the bed of the groove 9 and arranged at intervals longitudinally therein to register with 65 the slots 7 in the head 4 of the permanent portion of the rail.

13 are bolts extending through the bolt holes 7 and 12 and having their heads counter sunk in the top of the holes 7 so that 70 the upper surface of said heads will be flush with or below the surface of the slot 9.

14 are nuts on the lower end of the bolts 13 and abutting the under side of the side 5 of the head 4 and with the said bolts, firmly securing the separable and permanent heads 75 together.

The longitudinal slots 7 in the side 5 provide for any slight variation in the distances between the bolt holes in the separable head 80 so that there will be no difficulty in placing the said separable head in position besides allowing for the expansion and contraction of the metal.

The peculiar formation of the permanent 85 head 4 is quite important, as the difference in width of the sides 5 and 6 brings the actual tread portion of the separable head centrally over the web 3 and thus the weight of the car traveling on the rail is supported 90 vertically by the said web.

The permanent portion of the rail is made of the ordinary rail steel and is quite flexible and not liable to fracture easily, but the head 7 is preferably formed of high carbon or 95 manganese steel to resist wear. A composite rail is thus formed which will not be liable to break through crystallization, caused by vibration, as the weight is supported directly by the low carbon steel portion and 100 an upper running surface of a hard nature is provided to withstand the wear and tear of the car wheels.

The construction herein described has many advantageous features other than 105 those mentioned, the peculiar arrangement of the side flanges of the upper portion holding the said upper portion securely from side play and therefore preventing any spreading of the rails and when it is desired to replace 110 a worn rail it is not necessary to tear up a lot of the pavement but merely a few blocks

are removed to allow access to the bolts when the same may be loosened and the upper portion of the rail lifted clear and a new portion placed thereon without difficulty.

5 Not only is the pavement around the rails saved but a saving of much time and material is effected, as repairs may be made with great celerity. Another important feature in the use of a rail of this description is that

10 the tread portions may be arranged to break joint with the main portion so that there is no point in the rails where there is a break from top to bottom. This feature will

15 eliminate a considerable amount of vibration and noise.

What I claim as my invention is:—

In a device of the class described, in combination with a base, web and permanent head, said head being formed with a perfectly flat upper surface and arranged with a greater width on one side of said web than on the other and having pointed tips formed by the curved under surface converging to said flat surface and longitudinal slots

through the broader portion of said head, a 25 separable head having a longitudinal groove in its upper face intermediate of the width thereof and a recess formed by a curved hooked flange projection on the underside corresponding to and fitting over the pointed 30 tip of the narrow side of said permanent head, and a flange extending downwardly from the other edge having a sheer inner edge rounded outwardly at the bottom and a perfectly flat surface between said flanges 35 adapted to rest on the flat surface of said permanent head, and bolts countersunk in said separable head and extending through the longitudinal slots in said permanent head.

Signed at the city of Toronto, in the county of York, Province of Ontario, in the Dominion of Canada, this eighth day of February, 1908.

WILLIAM RITSON WILSON.
